2,178,336

REFRIGERATOR DEFROSTER

Clifford M. Chapman, Indianapolis, Ind., assignor of two-thirds to Russell R. Wilkinson and one-third to Avada Storm, both of Indianapolis, Ind.

Application September 18, 1937, Serial No. 163,544

3 Claims. (CL 62—1)

This invention relates to a defrosting device for refrigerator units which is particularly adaptable to mechanical refrigerators of the household type. In order that such refrigerators may be operated at the maximum efficiency, it is necessary to remove the frost on the refrigerating unit at periodic intervals. This is generally accomplished by stopping the refrigerating action and permitting the temperature within the refrigerator to rise above the freezing point for a sufficient length of time to melt the frost from the unit. The time consumed in defrosting the refrigerator by this method is relatively great since the temperature of the whole interior must be raised. This increase in temperature is also objectionable since it defeats the very purpose of the refrigerator.

Attempts have been made to defrost a refrigerator by electrical means by the use of a resistance heating unit placed in position to supply heat to the refrigerating unit. Such methods reduce the time required for defrosting and prevent an undue increase in temperature of the refrigerator. One object of the present invention is to provide an electrical means for defrosting the cooling unit of a refrigerator in the shortest time with the smallest rise in temperature of the refrigerator as a whole. This is accomplished by placing the heating element in such position that all, or nearly all of the heat generated therein is transmitted by direct conduction to the heat transfer surfaces of the cooling unit on which the frost collects.

Another object of the invention is to provide means for mounting the defrosting elements in such manner that they may be quickly assembled as an accessory in a refrigerator already in use and may be attached to various types and sizes of refrigerating units without mechanical change.

Other objects and features of the invention will be understood from the accompanying drawing and the following description and claims.

Fig. 1 is a sectional view through the upper portion of a household refrigerator showing the cooling unit in side elevation with a defrosting unit attached thereto. Fig. 2 is a perspective view of a portion of the defrosting unit.

In the form of the invention shown by way of illustration in the drawing, there is illustrated the upper portion of a refrigerator 10 having the usual door 11 and cooling unit 12 suitably mounted therein. The cooling unit herein shown is provided with a manifold 13 having connected thereto a plurality of refrigerant conductors 14 which pass down the side of the unit across the

bottom and upwardly to a similar manifold on the opposite side not shown. The refrigerant conductors 14 may be supplied with refrigerant at a low temperature in any well known manner and serve as the principal heat transfer surface of the cooling unit. They are normally in direct conductive relation with the walls of the unit 12 proper.

Beneath the unit 12 there is provided an electrical resistance heating element of a common form enclosed in a U-shaped metallic tube 15. Said tube is held in position beneath the unit by a supporting cross piece 16 having adjustable hooks 17 secured to its ends. A tension spring 18 is secured to the hooks 17 and passes over the unit 12. A metallic plate 19 is preferably interposed between the U-shaped tube 15 and the lower portion of the refrigerant conductors 14. The resistance element within the tube 15 is supplied with electricity by conductors passing through an insulated cable 20 to a switch 21 which is in turn connected by a cable 22 to any suitable source of electric current. The switch 21 is provided with a button 22a by means of which the current to the heating element may be manually turned on. The switch is provided with a thermostatic bellows 23 connected by a tube 24 to a thermostat bulb 25. The bulb 25 is placed in contact with the walls of the cooling unit and the bellows 23 operates the switch in a well known manner to turn off the heating current when the temperature at the bulb 25 rises sufficiently above the melting point to melt the frost on the unit.

By means of this construction, the defrosting of the refrigerator may be accomplished in a rapid and efficient manner with a minimum of attention from the housewife. It is only necessary for the housewife to operate the switch 21 without disturbing the action of the refrigerating unit. The heat from the resistance element within the tube 15 is largely transmitted by direct conduction to the plate 19 and distributed by said plate by direct conduction to the refrigerant conductors 14 and thence to the walls of the unit. The heat radiated from the tube 15 and the plate 19 to the interior of the ice box as a whole is a very small percentage of the heat generated, since these surfaces prior to defrosting are generally at a low temperature and are themselves covered with frost due to their direct conductive relation with the refrigerant conductors 14. The temperature of the heat transfer surfaces can be raised very rapidly and as soon as this temperature has increased to a point at which the frost will be melted,

the heat is automatically turned off without attention from the housewife.

The resilient mounting of the heating unit beneath the cooling unit provides that it may be quickly attached to almost any size of the cooling unit and, therefore, does not need to be designed to fit a particular refrigerator. It may be installed by unskilled labor and may easily be installed in refrigerators already in service. The 10 switch 21, of course, may be supported by any suitable means anywhere within the refrigerator.

While the foregoing specification describes in detail a preferred form of the invention, the various elements thereof may be varied by those 15 skilled in the art without departing from the scope of the invention as defined in the appended claims.

The invention claimed is:

1. In combination with the cooling unit of a 20 refrigerator, a plate of heat conducting material engaging at least a portion of the heat transfer surface of said cooling unit, an electrical resistance heating unit engaging the opposite face of said plate, an elongated tension spring passing 25 about said cooling unit, and means attached to

the ends of said spring for supporting said heating unit in contact with said plate, and said plate in contact with said cooling unit.

2. In a refrigerator having a cooling unit with refrigerant conductors arranged about the outside thereof, the combination of a plate of heat conducting material engaging at least a part of the outer surfaces of said refrigerant conductors, an electrical resistance heating unit engaging the opposite face of said plate, an elongated tension 10 spring passing about said cooling unit, and means attached to the ends of said spring for supporting said heating unit in contact with said plate, and said plate in contact with said cooling unit.

3. In combination with the cooling unit of a 15 refrigerator, an electrical resistance heating element, heat transfer means interposed between said element and at least a portion of the heat transfer surface of said cooling unit, an elongated tension spring passing about said cooling unit, and means 20 attached to the ends of said spring for supporting said heating element and said heat transfer means in heat transfer relation to said cooling unit.
